UNITED STATES PATENT OFFICE.

JOSEPH W. THOMPSON, OF SALEM, OHIO.

RIVETING-MACHINE.

SPECIFICATION forming part of Letters Patent No. 609,479, dated August 23, 1898.

Application filed October 7, 1896. Serial No. 608,150. (No model.)

To all whom it may concern:

Be it known that I, JOSEPH W. THOMPSON, of Salem, in the county of Columbiana and State of Ohio, have invented a certain new and useful Improvement in Riveting-Machines, of which improvement the following is a specification.

The object of my invention is to provide an appliance for eyeleting or riveting together sheets or strips of leather, pasteboard, or other comparatively soft material or fabric which shall be of simple and inexpensive construction and in the operation of which the rivet shall be effectively protected against displacement.

The improvement claimed is hereinafter fully set forth.

In the accompanying drawings, Figure 1 is a side view, partly in section, of a riveting-machine embodying my invention, the movable parts being shown in the positions occupied when in readiness for operation; Fig. 2, a similar view with the parts in the positions occupied at the conclusion of the operation; Fig. 3, a horizontal section at the line $\alpha\alpha$ of Fig. 1; and Figs. 4 and 5, vertical central sections, on an enlarged scale, through the lower right-hand portion of the machine, showing the parts in positions corresponding 30 with Figs. 1 and 2, respectively.

In the practice of my invention I provide a frame or body 1, which may be connected to any suitable base or support 2 and which is recessed or cut away on the side nearest the operative mechanism for the reception of the material α to be riveted and of members of said operative mechanism. An operating-lever 3, which is bifurcated at and adjacent to its inner end to clear a movable plunger 5, is pivoted to the upper portion of the frame 1 by a pin 4. The plunger 5 is fitted to reciprocate vertically in a boss or annular guide 6 on the frame and is externally threaded at and adjacent to its lower end (which is properly formed to split and turn over a rivet) to engage a cylindrical hub or boss 7 on the end of the upper arm of a U-shaped carrier 8, having a corresponding hub or boss 9 on the end of its lower arm 50 in line axially with the boss 7. The operating-lever 3 is coupled to the carrier 8 by links 10, fitting pins 11, projecting laterally from

the operating-lever, and pins 12, similarly projecting from the hub 7 of the upper arm of the carrier 8.

An anvil 13 is secured to the bottom of the frame 1 in line axially with the line of traverse of the plunger 3, and the lower boss 9 of the carrier 8 is bored out to fit truly around the anvil 13. When in position for operation, as shown in Figs. 1 and 4, the carrier, through the cylindrical passage 14 of its boss 9, forms a receptacle and guard for the rivet b , the head of which is set upon the top of the anvil 13, and the rivet is protected from displacement in the operation of the machine by said receptacle, which does not pass clear of its head until after it has penetrated the material to be riveted.

The threaded connection of the plunger and carrier enables the plunger to be adjusted to suit different thicknesses of material, as desired, and after adjustment the carrier and plunger form a rigid structure, which is accurately guided in its upward and downward movements by the bearing of the plunger in the boss 6 of the frame and the sliding fit of the lower boss 9 of the carrier on the anvil. The recess or space between the arms of the carrier admits of the requisite projection of the material on the inside of the axial line of the plunger and anvil.

In operation the rivet b is placed with its head on the top of the anvil 13, and the piece or pieces of material α to be riveted are rested on the lower boss 9 of the carrier. The operating-lever 3 is then pressed downward to the limit of its traverse, and the pressure of the connected plunger 3 on the material causes the rivet to penetrate and pass through the same, upon which the plain end of the rivet is split and turned over, thereby securing it firmly in the material.

I claim as my invention and desire to secure by Letters Patent—

1. In a riveting-machine, the combination, substantially as set forth, of an anvil, a plunger which is movable in line therewith, and a rivet-guard connected to and movable with the plunger, and guided on the anvil.

2. In a riveting-machine, the combination, substantially as set forth, of an anvil, a plunger which is movable in line therewith, a fixed guide for said plunger, and a rivet-guard con-

nected to and movable with the plunger, and guided on the anvil.

3. In a riveting-machine, the combination, substantially as set forth, of a frame or body, 5 an anvil fixed thereon, an operating-lever pivoted thereto, a plunger fitted to traverse in a guide on the frame in line axially with the anvil, a U-shaped carrier, having one of its

arms connected to the plunger and having a passage through its opposite arm which fits 10 freely around the anvil, and links coupling the carrier and operating-lever.

JOSEPH W. THOMPSON.
